CARL SCHWARTZ, OF NEW ROCHELLE, NEW YORK, ASSIGNOR TO INTERNATIONAL COMBUSTION ENGINEERING CORPORATION, A CORPORATION OF DELAWARE.

APPARATUS FOR GENERATING STEAM.

Application filed May 16, 1923. Serial No. 639,241.

This invention is directed to improvements in apparatus for generating steam, more particularly by the burning of pulverulent coal or other fuel adapted to be burned in suspension.

The primary objects of the invention are to simplify boiler and furnace construction and to better adapt the same for the burning of pulverized coal, oil or gas in substantial suspension or in cloud form; to more effectively burn the fuel; to more effectively apply the heat developed to the evaporating surfaces; to develop capacities in excess of those heretofore attained, and this, also, with a relatively small installation; while at the same time operating difficulties such as the formation of slag, rapid destruction of the brick work, etc., are effectually met and overcome.

The foregoing, together with such other objects and advantages as may hereinafter appear or are incident to my invention, I attain by means of the construction illustrated in preferred form in the accompanying drawings, wherein:

Fig. 1 is a cross section through an installation embodying my improvements, taken on the line 1—1 of Fig. 2; Fig. 2 is a section taken on the line 2—2 of Fig. 1; Fig. 3 is a section taken on the line 3—3 of Fig. 1; Fig. 4 is a section corresponding to Fig. 3, but illustrating a modification of my improvements; and Figs. 5 and 6 are sectional views illustrating details of the invention, Fig. 6 being taken on the line 6—6 of Fig. 5.

Referring now to Figs. 1 to 3 of the drawings, it will be seen that I arrange the boiler parts in a chamber A in such manner that the boiler and chamber define the combustion space. Three sides of the combustion space are defined by the boiler units B, C and D, each of which comprises banks of tubes 7, preferably substantially vertically disposed and connected at the bottom to mud drums 8, 9 and 10 and at the top to drums 11, 12 and 13. The drums 8, 9 and 10 are located in the bottom of the chamber A, being carried on the walls 14, forming the ash pit E. The drums 11, 12 and 13 are in the upper part of the chamber A. The fourth side of the combustion space is defined by the front wall 15 of the chamber A. The top wall or roof 16 of the chamber A closes the upper end of the combustion space, such wall being dropped down somewhat as indicated in

Figs. 1 and 2. A plurality of burners F supplies the pulverized coal, admitting it in a substantially vertical direction downwardly into the combustion chamber adjacent the front wall 15.

At the rear corners there are inwardly extending, diagonally disposed division walls 17 reaching from top to bottom.

The banks of tubes of the groups B, C and D are divided by the baffles 18 and 19 forming in conjunction with the furnace walls three passes. The baffles 19 are carried to the top of the combustion chamber and laterally extend from wall 17 to wall 17. The baffles 18 are carried down to the bottom and extend laterally to meet the wall 17. At the top of the three outermost or last passes of the respective groups are outlets 20 for the gaseous products of combustion, these leading to a stack, not shown. As the result of this arrangement the gaseous products of combustion cannot short circuit to the outlets but must travel through the passes formed by the baffles.

The operation, in case pulverized coal is used for firing, is as follows: The pulverized coal intermingled with carrying air is delivered to the burners through the pipes 21, the entering streams of intermingled coal and air traveling at a velocity in the neighborhood of 100 ft. per second, preferably, and being surrounded by additional air induced through the burner castings. The burners discharge the fuel adjacent the front wall. The total air supplied with the coal through the burner mechanism is sufficient to initiate ignition—say for example, from 30 to 40% of the total amount of air required for combustion. The coal and its carrying air travel at somewhat greater velocity than the air which is induced through the burner castings and as a result a slight measure of eddying is set up, thereby quickly instituting ignition and holding the flames well up toward the top wall or roof of the combustion space. The descending fuel is supplied with the additional air needed for combustion at successive points in accordance with the requirements of combustion, as combustion proceeds, through a plurality of auxiliary air inlets 22 formed in the front wall 15 of the chamber and arranged in rows, such inlets being damper controlled so that the proper amounts of air may be successively supplied.

The air admitted through the inlets 22 is

induced and it, therefore, travels at lower velocity than the descending fuel, and the fuel, therefore, travels past or is projected through slower moving bodies of air admitted substantially transversely of the direction of movement of the fuel, the result of which is that a slight eddying is set up securing proper admixture of the fuel and air; the fuel particles, as combustion proceeds, are successively brought into contact with air which has not been impoverished of its oxygen; the gases which emanate from the particles, as combustion proceeds, are stripped therefrom thereby exposing fresh surfaces of the fuel particles; and each particle, during its travel and as combustion proceeds, is ensured of being surrounded with air not impoverished of its oxygen. This manner of supplying the air needed for combustion directly meets two very important practical considerations; namely, first, that the fuel is progressing through the combustion space, and second, that combustion itself is a progressive operation. Thus combustion is rendered more perfect and the size of the furnace kept within practical limits. At the same time zones of localized intense heat in the flame are avoided.

It will be observed that the velocities are such that objectionable, violent eddying, as well as forcible impingement on any furnace or boiler part, is avoided.

A portion of the air admitted through the inlets 22 travels in a downward direction between the descending fuel and flame stream and the front wall, because of the force effect of the descending fuel stream and because of the difference in temperature between the entering air and the interior of the combustion chamber. This portion of the air protects the front wall against erosion. A portion also of the air, particularly that admitted in the lower rows of the inlets, borders the fuel and flame stream on its lower side providing a body of air into which the heavier unconsumed or partially consumed particles of fuel will gravitate and there find oxygen needed for combustion.

As combustion proceeds and gasification becomes more and more complete, the fuel and flame stream bends and reverses its direction of motion, this being brought about by the tendency of the hot gases to rise because of their lower specific gravity and also by reason of the draft. The combustion is completed within a space defined by the top wall 16, the bottom 23, the front wall 15 and the inner tubes of three groups B, C and D. For pulverized coal this space would be such that there would be approximately $\frac{1}{2}$ cu. ft. per lb. of coal burned. For oil burning, the size of this space could be cut down.

Air is supplied to the space between the descending and ascending portions of the fuel and flame stream through the upper

rows of inlets 22, a portion of the air induced therethrough passing inwardly between the streams of entering fuel before they unite into a single stream.

The descending portion of the stream of fuel and flame is subjected to the heat of the rising portion.

The gaseous products of combustion leave the combustion space passing to the sides and to the rear over the tops of the three baffles 18, then downwardly in the passes between the baffles 18 and 19, and then upwardly in the passes formed by the baffles 19 and the side and rear walls of the chamber A, leaving such passes through the outlets 20. The drawing of the gases to the sides and rear necessarily results in the spreading of the flames toward the sides and the rear, thus not only securing a more uniform application of heat to the three units but also making it possible to complete combustion in a combustion space of minimum vertical depth.

It will be seen from the foregoing that the groups of circulating tubes are located im-

mediately about or around the zone of highest temperature, whereas in existing practice, under stationary boilers, the evaporating surfaces are located at a point materially re-

moved from the zone of highest temperature.

At the same time the arrangement meets the requirements with respect to air admission in relation to fuel travel and the progress of

combustion peculiar to the burning of pul-

verized coal. It will further be noted that, broadly speaking, the gaseous products of

combustion are drawn laterally through the

banks of tubes to the outlets.

With such an arrangement it is not only possible to burn the coal most efficiently but also far greater boiler capacity is obtained.

The refuse matter which gravitates out of the gases of combustion at the inner passes of the boiler units may be readily removed through doors 24 which may be suitably located for this purpose.

With regard to the deposit of refuse matter which collects in the ash pit E, slagging may be prevented by admitting what would be a material excess of air through the clean-out doors 25 or elsewhere, such cooling air being admitted beneath the fuel and flame stream and providing a zone of relatively cooler temperature through which the refuse matter will gravitate and be cooled below the fusion point and which will absorb radiant heat from the deposit on the floor, maintaining its temperature below the fusion point.

I prefer, however, to prevent this slagging by means of a water screen G, located some distance above the floor 23 and comprising a plurality of tubes 26 connected at one end into the drum 9 and at the other end into a header 27, and the tubes 28 connected at one end with the header 27 and at the other end with the upper drum 12. This water screen is thus

a boiler unit, connected into the circulation of the boiler and its function is to absorb radiant heat from the deposit on the floor 23, preventing fusion thereof. In this connection the tubes 26 and 28 should be sufficiently apart to permit the refuse matter to freely pass to the bottom, but they should be in sufficient number to adequately cool the bottom of the combustion space to prevent the 10 slagging above referred to. It will be obvious that these tubes will be immediately below the zone of high temperatures and will materially assist in generating steam.

By using this water screen, I am enabled 15 to use only the amount of air practically required to effect combustion. Practically a slight excess of air over the theoretical necessary for combustion is required. Air cooling to prevent slagging requires still further 20 quantities of air, i. e., a material excess of air. Where a material excess of air is employed for cooling purposes, the temperature within the combustion space is uselessly lowered and limitations are imposed upon the 25 efficiency and the percentage of CO_2 obtainable; whereas with the water screen and only the amount of air required for combustion, maximum efficiency and CO_2 are obtainable.

To protect the top wall, this is cooled as by 30 making it hollow and passing a current of cooling air therethrough. This may be done by providing the burner castings with openings communicating with the space in the wall and during operation, air will be drawn 35 through the space and through the burner castings into the combustion chamber. This is shown in Figs. 5 and 6. It will be seen that by this arrangement the air which passes through the burner castings to intermingle 40 with the incoming fuel is preheated and ignition of the fuel is thus materially assisted.

In the arrangement of Fig. 4 the fuel is admitted at two ends of the combustion space and the two fuel and flame streams are bent inwardly toward each other and unite, passing 45 upwardly and then over baffles as before. In this instance, however, but two boiler units, B and D, and the water screen would be employed.

50 In both arrangements the overall length of the combined furnace and boiler is greatly reduced and the cross sectional area is not greatly increased, so that losses by external radiation of heat from the walls are not objectionable.

With respect to the burning of oil, substantially the same process is followed with the exception that a greater percentage of air is delivered from the burner mechanism with the oil and less is admitted through the auxiliary air inlets, some of the lower rows of which may be entirely closed.

In a furnace and boiler as described, the maintenance of the brick work is negligible

and the walls should remain in service without substantial repair practically indefinitely. There is no impingement on any refractories nor any slag deposit thereon which, in running down, would wash away the surface of the bricks. Should there be deposit on the 55 boiler tubes, this will be chilled below the fusion point and would build out in individual "hairs" or horns in a direction substantially opposite the direction of movement of the fuel and flame stream until they break off of their own weight. For all practical purposes, therefore, the boiler tubes remain 75 clean.

Generally speaking, to warrant burning pulverized coal under a stationary boiler, the 80 installation should be capable of meeting peak loads, of substantially continuous operation without shut downs for the removal of slag, and of developing an efficiency sufficiently greater than possible in stoker practice to more than pay for the cost of preparing and handling the coal, in addition to which the cost of brick maintenance must not be prohibitive. The arrangement described is one well adapted to fulfill all these 85 conditions and at the same time develop capacities far in excess of present arrangements.

Blistering of the tubes so characteristic of installations in which the flame or hot burning gases are forced into the tubes resulting in localized application of great heat, is avoided by my invention; the heat is more uniformly applied; and the losses are more than made up by the more effective application of radiant heat, in the passes.

What I claim is:

1. An arrangement for burning fuel in suspension including a chamber, means for admitting the fuel in a downward direction adjacent the front wall of the chamber, means for admitting auxiliary air into the chamber at the front thereof, and a boiler in the chamber adjacent the zone of high temperature and assisting in defining the combustion space, the gaseous products of combustion leaving from the upper part of the combustion space whereby the fuel and flame stream changes its movement from a downward to an upward direction in its travel through such space, such boiler including a plurality of tubes substantially vertically disposed and arranged on three sides of the chamber and the chamber having outlets in the upper part at the said three sides.

2. An arrangement for burning fuel in suspension including a chamber, a boiler in the chamber defining three sides and the bottom of the combustion space, the front and top walls of the chamber defining the other side and the top of the combustion space, means for admitting the fuel through the top wall in a downward direction, means for admitting air for combustion, and outlets for

the gaseous products of combustion at the said three sides of the chamber at the top.

3. An arrangement for burning fuel in suspension including a chamber having boiler units arranged along three sides thereof, division walls between adjacent boiler units, burner means for admitting the fuel substantially vertically downward adjacent the fourth side and in a plane at the top of the 10 boiler units, and an outlet from the chamber for the gaseous products of combustion adjacent the top of each boiler unit.

4. An arrangement for burning fuel in suspension including a chamber having boiler units arranged along three sides thereof, each boiler unit having an upper and lower drum and banks of upright tubes connecting corresponding upper and lower drums for admitting the fuel substantially vertically 15 downward, burner means adjacent the upper drums, and outlets from said chamber for

the gaseous products of combustion adjacent the upper drums.

5. In combination, a pulverized fuel burning boiler furnace, means for admitting fuel 25 to be burned in space therein, a water screen in the lower portion of said furnace including a row of tubes inclined somewhat from the horizontal, a boiler having upper and lower drums, a bank of substantially upright 30 tubes connecting the drums and exposed to radiant heat, upcomer connections for the tubes of the water screen, comprising a row of tubes connecting into the upper drum, which tubes are substituted for and form the 35 front row of tubes of said bank and means for supplying the said water screen with water.

In testimony whereof, I have hereunto signed my name.

CARL SCHWARTZ.
